UNITED STATES PATENT OFFICE.

WILLIAM McCALLUM, OF HALIFAX, ENGLAND, ASSIGNOR TO JOSEPH WILD & CO., OF NEW YORK CITY.

DESIGN FOR A CARPET-PATTERN.

Specification forming part of Design No. 5,279, dated September 26, 1871.

To all whom it may concern:

Be it known that I, WILLIAM McCALLUM, of Halifax, in the county of Yorkshire, England, have invented a new and original Design for a Carpet, of which the following is a specification:

The nature of my design is fully represented in the accompanying colored sketch, to which reference is made.

I claim as my invention—
The design for a carpet, as shown.

WILLIAM McCALLUM.
